United States Patent Office

Des. 190,141
Patented Apr. 18, 1961

190,141

BOTTLE

Brooks D. Fuerst, Sylvania, and Harry M. Sinclair, Jr.,
Port Clinton, Ohio; said Fuerst assignor to Owens-
Illinois Glass Company, Toledo, Ohio, a corporation of Ohio, and said Sinclair assignor to The Sinclair
Manufacturing Company, Toledo, Ohio, a partnership

Filed July 19, 1960, Ser. No. 61,535

Term of patent 14 years

(Cl. D58—8)

Fig. 1 is a side elevational view of a bottle showing our design. The side not shown in Fig. 1 is the same as that shown.

Fig. 2 is a top plan view of the same.

We claim:

The ornamental design for a bottle, substantially as shown and described.
